[57] CLAIM

The ornamental design for a bicycle-mountable bag, as shown and described.

DESCRIPTION

FIG. 1 is a front elevational view of a bicycle-mountable bag showing my design;

FIG. 2 is a perspective front view thereof;

FIG. 3 is a perspective rear view thereof;

FIG. 4 is a perspective front view as mounted on a bicycle thereof;

FIG. 5 is a perspective front view with vertically ex-

tended flap for dismounting thereof;

FIG. 6 is a perspective inside view fully stretched showing paper holding compartment, computer floppy disk and calculator pockets thereof;

FIG. 7 is a top plan view thereof;

FIG. 8 is a bottom plan view thereof;

FIG. 9 is a left end elevational view thereof; and,

FIG. 10 is a right end elevational view thereof.

The broken line showing of a bicycle or parts thereof in FIGS. 1, 2 and 4 is for illustrative purposes only and forms no part of the claimed design.
